UNITED STATES PATENT OFFICE.

HENRY E. ELLSWORTH, OF SIMSBURY, CONNECTICUT, ASSIGNOR TO THE ENSIGN-BICKFORD COMPANY, OF SIMSBURY, CONNECTICUT, A CORPORATION OF CONNECTICUT.

MANUFACTURE OF FUSE.

No. 920,119.

Specification of Letters Patent.

Patented May 4, 1909.

Application filed February 17, 1909. Serial No. 478,447.

To all whom it may concern:

Be it known that I, HENRY E. ELLSWORTH, a citizen of the United States, and a resident of the town of Simsbury, in the State of Connecticut, have invented certain new and useful Improvements in the Manufacture of Fuse, of which the following is a specification, reference being had to the accompanying drawings, forming a part hereof.

10 This invention relates to improvements in the manufacture of fuse and especially of fuse embodying the invention set forth in my application for U. S. Letters Patent filed May 4, 1908 and serially numbered 430,689. 15 In that application I have shown and described a continuous fuse which will not fire through or spit and which is accordingly adapted for use in such cases as where a charge is required to be fired from the bottom of a long hole. In such cases the fuse is often lead through the powder for a considerable distance and obviously should not communicate any fire to the powder except at the end of the fuse. Fuse embodying 20 said invention may be manufactured in different ways, but the present method of manufacture is particularly adapted to produce a finished fuse of the desired quality.

In accordance with the present invention, 30 cotton yarns or the like are first impregnated with a fire proofing liquid such as a solution of sodium silicate diluted with hot water to 27° Baumé and are then spun about the powder or other fire-conveying medium. 35 It matters not whether the spinning is done in the ordinary manner by feeding the powder in its natural state into the impregnated threads as they are being spun; or whether first a core of powder is provided, such as 40 could be done by incasing the powder in a small cotton envelop and striking it in with asphaltum, which core is then over-spun by the impregnated yarns. In both cases the result is the same. After the spinning operation, the fuse is passed through asphaltum or 45 some other suitable varnish and closely wiped, a step known as "striking in", for the purpose of cementing the spinning threads together and of giving a good foundation for 50 a water proof coating.

In order to impart the water proofing qualities to the fuse, a gutta percha mixture is next applied in any well known manner. Finally the fuse is finished by countering it with a number of strands of cotton yarn and 55 by passing the countered fuse through some suitable finishing material as for instance a mixture of china clay or glue.

It will be obvious that the water proofing is not an essential step of the present method 60 and that the finishing process may be varied without departing from the spirit of the invention.

I claim as my invention:

1. The method of manufacturing fuse, 65 which consists in treating the spinning yarns to render them fire proof, and spinning the yarns about the fire-conveying medium.

2. The method of manufacturing fuse, 70 which consists in treating yarns to render them fire proof, spinning the yarns about the fire-conveying medium, striking in with a varnish, and then countering the fuse.

3. The method of producing fuse described herein, which method comprises the feeding 75 into a fire proof substance of a medium for conveying the fire.

4. The method of producing fuse described herein, which method comprises the spinning of fire proof strands about a medium for conveying the fire. 80

5. The method of producing fuse described herein, which method comprises the treating of strands of threads with a fire proofing solution, spinning the strands, and feeding a 85 medium for conveying the fire into the strands as they are being spun.

6. The method of producing fuse as described herein, which method comprises the spinning of fire proof strands about a medium for conveying the fire, and covering the spun strands. 90

This specification signed and witnessed this twelfth day of February, A. D., 1909.

HENRY E. ELLSWORTH.

Signed in the presence of—

ROBERT DARLING,
CHAS. A. BUERMAN.
